UNITED STATES PATENT OFFICE.

WILLIAM J. GOLIGHTLY, OF KOKOMO, INDIANA, ASSIGNOR TO PITTSBURGH PLATE GLASS COMPANY, A CORPORATION OF PENNSYLVANIA.

GLASS-CASTING TABLE.

1,366,786.

Specification of Letters Patent. Patented Jan. 25, 1921.

Application filed April 8, 1919. Serial No. 283,610.

To all whom it may concern:

Be it known that I, WILLIAM J. GOLIGHTLY, a citizen of the United States, and a resident of Kokomo, in the county of Howard and State of Indiana, have made a new and useful Invention in Glass-Casting Tables, of which the following is a specification.

The invention relates to casting tables for use in the making of plate glass, and has for its principal object the provision of an improved construction for keeping the surface of the table flat throughout the continued use of the table so that the glass sheets cast upon the tables will be of substantially uniform thickness.

The ordinary casting table gradually bows up from the edges to the center as the table gets hotter and hotter from repeated casting operations, and as a result the glass sheets which are formed on the table by teeming the molten glass thereon and spreading it out by a roller, are thinner at the center than at the edges. It has been attempted to remedy this difficulty by placing shims or wedges under the corners of the table so that the weight of the table is borne at these points and such weight tends to cause the table to sag at the center, thus counteracting to a certain extent, the bowing up tendency. However, in the use of this expedient there has been a tendency of the table to sag unequally, and there were no means for adjusting the amount of sag to the varying heat condition of the table. The present construction is designed to eliminate the tendency of the table to bend or sag unequally and to provide a means for keeping the table flat from the time it arrives at such a degree of heat that it tends to start bowing until a maximum temperature is reached.

Briefly stated these results are achieved by employing adjusting screws at the corners of the table and having these screws engage transverse stiffening bars so that any tendency to sag when the screws are adjusted to take the weight of the table is distributed equally across the width thereof. The adjustment of the screws is started when the table reaches a temperature such that it would otherwise begin to bow up, and this adjustment is continued until the table reaches a maximum degree of heat. One

embodiment of the invention is illustrated in the accompanying drawing, wherein:

Figure 1 is a side elevation of the table; Fig. 2 is a section on the line II—II of Fig. 1; Fig. 3 is an enlarged section at one end of the table on the line II—II of Fig. 1; Fig. 4 is an enlarged side elevation of one end of the table, and Fig. 5 is a plan view of the table.

The table itself may be of any approved type and comprises a series of longitudinally extending sections 1, secured together by transverse tie rods 2. This table is mounted upon transverse foundation plates 3, 4 and 5, which are in turn mounted upon a base 6 of concrete or other suitable material. At the leeward end of the table the plate 3 and table are held against relative longitudinal movement by means of the key 7, which extends from one side of the table to the other, as indicated in Fig. 2. At the other end of the table, a transverse bar 8 extends from one side of the table to the other, but is seated entirely in the foundation plate 5, so that its upper surface is flush with the upper surface of the foundation plate, thus permitting the end of the table to move over the plate as the length of the table changes by reason of temperature conditions.

Mounted upon the ends of the foundation plates are the blocks 9, such blocks being rigidly secured to the foundation plates by any suitable means, such as the stud bolts 10. Extending through these blocks 9 are the set screws 11. These set screws engage the ends of the key 7 and bar 8 and constitute a means whereby an adjusting force may be applied, tending to lift the corners of the table upward.

The adjusting screws do not come into play until the casting operation has been under way for several hours, as it takes the table a considerable time to heat up sufficiently to cause a noticeable bowing thereof. The adjustment of the screws is then made gradually, a fraction of a turn at a time, so that as the tendency of the table to bow up at the center increases, more and more force is applied by the screws, tending to support the table at its side edges and thus producing a tendency of the table to sag intermediate its edges and thus counter-

acting the bowing tendency. The table finally arrives at a maximum heat, after which no further adjustment of the screws is necessary, and at such time the screws will 5 have been adjusted such a distance as to produce a sag of perhaps one sixteenth of an inch if the table had not been heated. At such time, however, the upper surface of the table will lie in a horizontal plane, due to 10 the fact that the tendency to sag is counteracted by the bowing tendency incident to the expansion of the table resulting from its increased temperature.

The application of the lifting force of the 15 screws to the bars 7 and 8 instead of directly to the side sections of the table, is advantageous in that the tendency to sag is thus distributed throughout the entire width of the table instead of the major part of 20 the sagging occurring at the side edges of the table, as would be the case if the bars 7 and 8 were not employed and the screws were applied directly to the side sections. The sections of the table are securely bolted 25 together by means of the tie rods 2, but such securing means are not sufficient to overcome the tendency to unequal sagging, such as would occur without the transverse bars 7 and 8.

30 It will be understood that the invention is not limited to the particular table shown, which is preferably water cooled, as indicated by the passages 13, and which overhangs the foundation plates 3, 4 and 5 (Fig. 35 3), but that the invention is applicable to tables which are not water cooled and to tables which do not overhang the foundation plates, only slight changes in construction being required to adapt the invention 40 to widely varying types of apparatus. The invention provides for the maintenance of the upper surfaces of the table perfectly flat during the entire casting operation, thus insuring that the plates of glass cast thereon 45 shall be of substantially uniform thickness from edge to edge.

What I claim is:

1. In combination, a plate glass casting table, foundation means therefor, transverse 50 bars between the foundation means and the table, and adjusting means at the ends of

said bars for applying force thereto, tending to lift the table.

2. In combination, a plate glass casting table, foundation plates extending transversely of the table at the ends thereof, 55 transverse bars on the upper sides of the plates, and screw adjusting means at the ends of said plates for applying force upwardly to said bars.

3. In combination, a plate glass casting table, foundation plates extending transversely of the table at the ends thereof, 60 transverse bars on the upper sides of the plates, and screw adjusting means at the ends of said plates for applying force upwardly to said bars, one of said bars being seated in both the plate and table and serving to maintain the table against movement at such point.

4. In combination, a plate glass casting table, foundation plates extending transversely of the table at the ends thereof, 65 transverse bars on the upper sides of the plates, and screw adjusting means at the ends of said plates for applying force upwardly to said bars, one of said bars being seated in one of the plates so that its upper surface is flush with the upper surface of such plate.

5. In combination, a plate glass casting table, foundation plates extending transversely of the table at the ends thereof, 70 transverse bars on the upper sides of the plates, and screw adjusting means at the ends of said plates for applying force upwardly to said bars, one of said bars being seated in both its plate and the table so as to act as a key, and the other bar being seated in its plate so that its upper surface 75 is flush with the upper surface of such plate.

6. In combination, a plate glass casting table made up of a plurality of longitudinal sections secured together, foundation means therefor, transverse bars between the foundation means and the table and means at the ends of the bars for adjusting said ends 80 upwardly.

In testimony whereof, I have hereunto 85 subscribed my name this 2d day of April, 1919.

WILLIAM J. GOLIGHTLY.
